UNITED STATES PATENT OFFICE.

FRANCIS H. RICHARDS, OF HARTFORD, CONNECTICUT, ASSIGNOR TO THE KEMPSHALL MANUFACTURING COMPANY, OF ARLINGTON, NEW JERSEY, A CORPORATION OF NEW JERSEY.

PLAYING-BALL.

SPECIFICATION forming part of Letters Patent No. 712,414, dated October 28, 1902.

Application filed July 22, 1902. Serial No. 116,500. (No model.)

To all whom it may concern:

Be it known that I, FRANCIS H. RICHARDS, a citizen of the United States, residing at Hartford, in the county of Hartford and State of Connecticut, have invented certain new and useful Improvements in Playing-Balls, of which the following is a specification.

This invention relates to playing-balls, especially those used in golf; and its object is to furnish at low cost a durable ball which has great flying power but is dead under a light blow.

In the drawings forming a part of this specification, Figure 1 is an enlarged sectional view of a segment of a ball made in accordance with my improvements. Fig. 2 is a part-sectional view of a completed ball. Fig. 3 is a part-sectional view illustrating one kind of core or inner ball. Fig. 4 is a part-sectional view illustrating a stage in completing a core. Fig. 5 is a view of the preferred form of rubber shell employed in the interior of the core, this view showing the shell in its normal or unexpanded condition.

Throughout the views similar parts are designated by similar characters of reference.

Upon a shell 1 of solid rubber I wind face-wise and continuously in different directions a strip 2 of paper to form a core or inner ball A. I prefer to use "all-rope Manila" paper in a strip or strips about three-eighths of an inch wide, which I wind in a state of high tension. Owing to the thinness of the windings and to the tension of the paper I make a ball 35 or core which is solid, and consists of a multitude of thin layers tensioned in all directions. Before the paper is wound on the hollow 3 within the rubber shell 1 may be filled by a center piece 4, of gutta-percha or other material, 40 which may be injected through a hollow stem 5, formed for convenience upon the shell 1. In some cases, however, a center piece 4 need not be provided before the winding on of the paper.

Owing to its compactness, as well as to the tensioned condition of its layers, the core A is highly resilient under a heavy blow, this quality being increased by the presence of the soft-rubber sphere or layer 1 within the pa-

per shell and being further increased by the presence of a hard center, as 4, within the soft rubber.

Before applying a shell to the core A, I prefer to inject softened or fluent material 4^a under pressure to an extent to expand both the rubber sphere 1 and also the layers comprising the paper shell, as illustrated at Fig. 4. The material 4^a, which is preferably gutta-percha, may be injected while hot through a nozzle 6, inserted in the tubular stem 5, force 6^a being applied to the fluent gutta-percha by means of a piston. The pressure may be made very high, to the end not only to tension the rubber shell 1, and thereby increase its liveliness, but also to tension the paper 65 windings practically to the limit or nearly to the breaking-point, and compact them into a solid or highly-compressed shell, which, by reason partly of its solidity and partly on account of its longitudinal tension, is extremely 70 lively under a hard blow. Upon the core thus formed I apply a shell 7, preferably of gutta-percha, and preferably holding the core A under high compression.

It will be observed that owing to the mobility of the tensioned soft-rubber shell 1^a within the compressed paper-wound sphere the latter is to some extent compressible, although owing to the solidity of said rubber shell 1^a and of the injected core 4^a, as well as to the tension of the paper layers, said expanded paper shell A' tends instantly upon being depressed to recover its normal shape, this tendency being highly augmented by the elasticity developed in the paper itself when 85 stretched to the proper limit. It will be further understood that owing to the constant compression by the shell 7 of the compressible tensioned paper sphere A' with its solid mobile interior the whole ball tends instantly to 90 recover its spherical form upon being distorted by a blow, and hence the flying power of the ball is rendered phenomenal. It will also be understood that the compressed sphere A' is very hard and not much affected 95 by a light blow, and that the same is also true of the shell 7, so that for "putting" the ball is dead, and hence desirable for the game.

It will be perceived that the structure shown at Fig. 3 may be covered by a shell without first expanding the rubber and paper shells, although I prefer such expansion for 5 the reasons given.

Variations in construction and other particulars may be resorted to within the scope of my invention, and portions of my improvements may be used without others.

10 Having described my invention, I claim—

1. A playing-ball comprising strips of paper wound facewise and tensioned nearly to the breaking-point and forming a substantial sphere, and a cover of wear-resisting material

15 upon said sphere.

2. A playing-ball comprising a center piece of yielding material, windings of flat paper strip thereon tensioned nearly to the breaking-point and forming a substantial sphere, 20 and a hard cover upon said sphere.

3. A playing-ball comprising a center piece of soft rubber, windings of flat paper strip thereon tensioned nearly to the breaking-point and forming a substantial sphere, and 25 a cover of gutta-percha.

4. A playing-ball comprising a small sphere of hard material, a shell of soft rubber thereon, windings of flat paper strip upon said rubber shell and tensioned nearly to the breaking-point, and a cover of gutta-percha holding 30 said paper under compression.

5. A playing-ball comprising a sphere of tensioned rubber, windings of flat paper strip thereon and tensioned nearly to the breaking-point, and a shell of plastic material. 35

6. A playing-ball comprising a small, hard body, a layer of tensioned rubber thereon, tense windings of flat paper strip forming a substantial layer upon said rubber layer, and 40 a shell of plastic material holding said paper under compression.

7. A playing-ball comprising a compressed sphere consisting of tight windings of flat paper strip, and a sphere of mobile material filling 45 said paper sphere, and tending to expand the same.

8. A playing-ball comprising a compressed sphere consisting of tight windings of flat paper strip, a sphere of mobile material filling 50 said paper sphere, and a hard shell upon said paper sphere.

9. A playing-ball comprising a compressed sphere consisting of tight windings of flat paper strip, a sphere of mobile material filling 55 said paper sphere and tending to expand the same, and a hard shell holding said paper sphere under compression.

10. In a playing-ball, a sphere of paper distended by a core of plastic material injected 60 thereinto, and a hard cover.

11. In a playing-ball, a sphere of paper distended by mobile material injected thereinto, and a hard cover, said paper being in a state 65 of compression between said injected substance and said cover.

12. In a playing-ball, a sphere of paper distended by gutta-percha injected thereinto.

13. In a playing-ball, tight windings of paper forming a substantial shell, said shell being distended by mobile material injected 70 thereinto, and a hard cover upon said paper.

14. In a playing-ball, tight windings of fibrous material forming a substantial shell, said shell being distended by mobile material injected thereinto, and a hard cover holding 75 said shell under compression.

15. In a playing-ball, tight windings of paper strip forming a substantial shell, said shell being distended by a hard injected body, and a cover of gutta-percha holding said paper 80 under compression.

16. In a playing-ball, a hard sphere of packed paper, and a sphere of distorted rubber within said paper sphere.

17. In a playing-ball, a sphere consisting 85 of compressed layers of paper, a sphere of distended rubber under compression within said sphere, and a cover of wear-resisting material upon said paper sphere.

18. A playing-ball comprising a distorted 90 rubber sphere, a sphere consisting of windings of flat paper strip tensioned nearly to the breaking-point, and a gutta-percha sphere.

19. A playing-ball comprising a gutta-percha cover and spheres of packed paper and 95 distorted rubber held under compression by said cover.

20. A playing-ball comprising a gutta-percha cover and spheres of paper and distorted rubber held under compression by said cover; 100 said paper consisting of tight flat windings of paper strip.

21. In a playing-ball, a sphere of paper distended by plastic material injected thereinto, a sphere of soft yielding material intervening 105 between said paper and said injected material, and a hard cover.

22. In a playing-ball, a sphere of paper distended by mobile substance injected thereinto, a sphere of soft rubber intervening between 110 said paper and said injected material, and a hard cover.

23. In a playing-ball, a sphere of paper distended by mobile substance injected thereinto, an expanded sphere of soft rubber intervening between 115 said paper and said injected material, and a hard cover holding said paper under compression.

24. In a playing-ball, a sphere consisting of tight windings of paper, said sphere being 120 compressed and said windings distended by mobile material injected thereinto, and a hard cover.

25. In a playing-ball, a sphere consisting of tight windings of paper, said sphere being 125 compressed and said windings distended by mobile material injected thereinto, a layer of mobile material intervening between said paper and said injected material, and a hard cover. 130

26. In a playing-ball, a cover of plastic material holding under compression an expanded layer of paper, an expanded layer of rubber, and a hard central body.

27. In a playing-ball, a cover of gutta-percha holding under compression an expanded layer consisting of tight windings of paper, an expanded layer of rubber, and a hard central body.

28. In a playing-ball, a substantial shell consisting of tight windings of paper strip, said shell being distended by plastic material

injected thereinto, a tensioned layer of rubber intervening between said plastic material to and said shell, and a cover of gutta-percha holding said paper under compression.
